(57) **CLAIM**

The ornamental design for a bag, as shown and described.

DESCRIPTION

FIG. 1 is a top, front, left perspective view of a bag showing our new design;

FIG. 2 is a front view thereof;

FIG. 3 is a rear view thereof;

FIG. 4 is a left side view thereof;

FIG. 5 is a right side view thereof;

FIG. 6 is a top, front, left perspective view of an alternative claimed configuration of a bag showing our new design;

FIG. 7 is a top, front perspective view thereof;

FIG. 8 is a top, front, left perspective view of an alternative claimed configuration of a bag showing our new design; and,

FIG. 9 is a top, front perspective view thereof.

The portions of the bag shown in broken lines form no part of the claimed design.

The grayscale contrast represents a contrast in appearance only and does not represent any particular color, material, texture or finish.
